Inventor
Joseph Farris
Walter M. Fuller

UNITED STATES PATENT OFFICE.

JOSEPH FARRIS, OF SPRINGFIELD, ILLINOIS.

WATER BASE FOR FURNACES.

Application filed December 1, 1927. Serial No. 237,026.

My invention pertains to humidifying or conditioning appliances for hot air furnaces and similar structures and represents a betterment relative to the construction presented in my earlier United States Patent No. 1,410,664, furnace constructions, granted March 28th, 1922.

As is well known, houses heated by hot air require that a certain amount of moisture be supplied to the air to maintain it in suitable condition for performing its intended function.

The degree of dampness or relative humidity depends upon several factors, such as the amount of water surface exposed to the air, the temperature of the water, the manner in which the air and water vapor are brought together, etc.

Different conditions and the varying personal peculiarities of individuals require that the humidifying appliance of a hot air furnace should be subject to adjustment or control so that the particular demand for each installation may be satisfactorily met.

I have found that it is desirable and convenient to be able to modify or change the temperature of the water and to vary the extent of water-surface exposed most directly to the heating influence of the furnace to control or govern the humid condition of the air delivered by the heater.

Accordingly, in the novel and improved moisture-supplying device of this patent, the water under the ash-pit compartment of the furnace is subject to substantial changes in order to effect the required degree of humidity of the air, the other water of the humidifying structure remaining unchanged and performing its customary function.

To enable those acquainted with or trained in this art to have a full and complete understanding of the invention, both from structural and functional standpoints, in the accompanying drawing, forming a part of this specification, I have illustrated a present desirable and preferred embodiment of the invention in detail and I have employed the same reference characters throughout the several views to designate like parts.

In this drawing: Figure 1 is a horizontal section through the lower portion of the furnace on line 1—1 of Figure 2;

Figure 2 is a vertical section through such lower part of the furnace on line 2—2 of Figure 1;

Figure 3 is a fragmentary front elevation of the structure; and

Figure 4 is a vertical fragmentary section on line 4—4 of Figure 1.

Referring to this drawing, it will be observed that the furnace appliance includes a round, or other suitably-shaped, base-pan or tray having a bottom wall or floor 11 and an upstanding border or marginal flange or rim 12, thus providing a relatively shallow compartment or base adapted and intended to accommodate some of the humidifying water.

Such pan also has a rib 13 which, with that portion of the flange 12 between its ends and a central division rib 14, provides two water chambers 15 and 16 directly beneath the bottom-wall or floor 17 of the ash-pit chamber 18.

In order to provide for drainage of the three water receptacles, the flange or rim 12 is supplied with suitably-positioned threaded holes 19, 20, 21 and 22 therethrough which are normally closed by removable screw-threaded plugs 23, any one or more of which may be taken out when it is desired or required to drain off the liquid contents of the one or more water-containing receptacles.

The upstanding rib 13 has similar threaded holes 24 and 25 near its ends or at any other convenient location which may or may not be closed or filled with the threaded plugs 26 and 27 respectively.

When thus closed, the water poured into the outer pan through the one or more doorways 28 cannot find entrance into either of the compartments 15 and 16 so that the latter perform no substantial function in producing the humidifying conditions.

If, however, either one or both of such plugs are removed, then water flows into one or both of the chambers where it becomes

substantially heated by the heat of the overlying ash-pit member, such variable or adjustable amount of liquid surface exposed to such heat correspondingly increasing the amount of moisture delivered to the air flowing through the furnace.

Either one or both of such inner chambers may be closed off, by the use of the corresponding plug, under which circumstances the humidifying action of the appliance as a whole is conformably reduced.

When the water in such inner chamber or chambers is used, there is sufficient air leakage around such compartment or compartments to materially increase or augment the amount of moisture delivered to the air.

The water in such underlying chambers may be in actual contact with the bottom face of the ash-pit floor or its level may be below such surface as circumstances may dictate.

From the foregoing it will be apparent that the action of the furnace so far as air humidifying or conditioning requirements are concerned may be adjusted, modified, or varied by controlling the amount of water under the ash-pit floor so that any reasonable humidifying condition may be complied with.

The invention is not limited or restricted to the precise and exact details of structure presented and these may be modified within comparatively wide limits without departure from the heart and essence of the invention as defined by the appended claims

and without the loss or sacrifice of any of its substantial or material benefits or advantages.

I claim:

1. In a hot-air furnace, the combination of a base-plate having an upstanding marginal flange forming a pan adapted to contain a supply of humidifying water, a rib on said plate conforming approximately to the contour of the ash-pit floor of the furnace and forming a chamber beneath such floor adapted to contain humidifying water, and means to open or close communication between said pan and chamber, whereby the latter may selectively be used or not used for humidifying purposes in association with the water in said pan.

2. In a hot-air furnace, the combination of a base-plate having an upstanding marginal flange forming a pan adapted to contain a supply of humidifying water, a rib on said plate conforming approximately to the contour of the ash-pit floor of the furnace and forming a receptacle also adapted to hold humidifying water, a rib dividing said receptacle into non-communicating parts, and means to open or close communication between said individual receptacle parts and said pan, whereby either or both or neither of said receptacle parts may be used for humidifying purposes in association with the water in said pan.

In witness whereof I have hereunto set my hand.

JOSEPH FARRIS.
